(57) **CLAIM**

The ornamental design for a toy figure, as shown and described.

DESCRIPTION

FIG. 1 is a front elevation of a toy figure in accordance with the present invention;

FIG. 2 is a first side elevational view thereof;

FIG. 3 is a rear elevational view thereof;

FIG. 4 is an opposite side elevational view thereof;

FIG. 5 is top plan view thereof;

FIG. 6 is a bottom plan view thereof;

FIG. 7 is a top, front perspective view thereof; and,

FIG. 8 is a bottom, rear perspective view thereof.

The broken lines showing facial features in FIGS. 1, 2, 4 and 7 are for illustrative purposes only and do not form part of the claimed design.
